ATTORNEYS.

UNITED STATES PATENT OFFICE.

ELI Z. WHITE, OF CARROLLTON, MISSISSIPPI.

HAND-POWER MECHANISM.

SPECIFICATION forming part of Letters Patent No. 309,670, dated December 23, 1884.

Application filed July 1, 1884. (No model.)

To all whom it may concern:

Be it known that I, ELI Z. WHITE, of Carrollton, in the county of Carroll and State of Mississippi, have invented certain new and useful Improvements in Hand-Power Mechanism, of which the following is a full, clear, and exact description.

The object of my invention is to provide a simple, efficient, and inexpensive hand-power mechanism for driving railway hand-cars or vehicles, or for operating light machinery.

The invention consists in a hand-power mechanism constructed with a drive-wheel mounted on a main shaft, which carries a loose rock-lever, which in turn connects by rods with reversely-set cranks of two shafts carrying drive-wheels which act on the drive-wheel of the main shaft, and also in mounting the crank-shafts yieldingly, so as to be self-adjusting to irregularities in the contact-faces of the friction drive-wheels, and so as to be adjustable to regulate the frictional contact of the wheels.

The invention consists, also, in various details of construction and combination of parts of the mechanism, all as hereinafter fully described and claimed.

Reference is to be had to the accompanying drawings, forming a part of this specification, in which similar letters of reference indicate corresponding parts in all the figures.

Figure 1 is a sectional side elevation of a railway hand-car with my improvement applied. Fig. 2 is a plan view thereof. Fig. 3 is an enlarged detail view of the connections between the hand-lever and the connecting-rods. Fig. 4 is a sectional elevation taken on the line $x-x$, Fig. 3, and Figs. 5 and 6 are diagram views illustrating modifications of the improvement.

By way of illustration I herein show and describe my improvement as applied to drive a railway hand-car; but it is applicable also to drive or operate sewing-machines, churning, and a large variety of light machinery by connected pulleys and belts or other gearing.

The letter A indicates the frame of a railway hand-car, B B the opposite main wheels of the car, and C the guide-wheel of the car, which may run either in front or behind the wheels B. The wheels B B are mounted on an axle, D, which is journaled or held in suitable

hangers, a, pendent from the frame A at each side of the car.

E E' are two shafts, each of which is journaled at opposite sides of the car in boxes or blocks F, which are fitted to slide in openings g of the hangers G, which are fixed to the frame A in any suitable manner. Springs H are held in the openings g of the hangers G, 55 so as to bear against the outer ends of the boxes F, and suitable plates with thumb-screws or set-screws I are provided for forcing the boxes inward to carry the peripheries of the friction-wheels J J', mounted, respectively, on the shafts E E', against the periphery of the drive-wheel K, which is fixed to the shaft or axle D of the car-wheels B B, and so that when the friction-wheels J J' are revolved in the same direction against opposite points at the periphery of wheel K the latter will be turned to carry the car forward or backward. The adjustment of the boxes F by the springs H and screws I allows the friction-wheels J J' to be pressed against the drive-wheel K with more or less force, as required, depending on the weight of the car, the load carried by it, or the speed of travel desired; and the tension of the springs permits the boxes to yield or give way somewhat to compensate for any irregularity in the contact-surfaces of the three friction-wheels, and always insure a close driving contact of the wheels with each other. The meeting faces or peripheries of the friction-wheels will be covered with rubber or other suitable fabric, to prevent slip of the wheels on each other without driving effect. One or more hanger-braces, L, having a bearing for the shaft D and fastened to cross-bars of the frame A, may be 80 used at one or both sides of the driving-wheel K, to prevent vibration of the parts. The shafts E E' have, respectively, the reversely-set cranks e e', to which cranks the ends of the connecting-rods M M' are journaled. These 85 rods M M' are connected to the arms of a lever, O, at opposite sides of the shaft D and at equal distances from the shaft, and the lever O has an elongated bearing on the shaft, or on a bushing fitting loosely thereon, so that 90 when the lever is rocked on the shaft the rods M M' will turn the shafts E E', and with them the friction-wheels J J' K, in the direction of their arrows, for moving the car, which may

thus be run in either direction by working the lever.

To provide for changing the lengths of the connecting-rods $M M'$ as the boxes F are moved 5 along the slots g , and maintain the connections of the rods $M M'$ with the lever O at the same points, and also the proper reverse positions of the cranks $e e'$, I slot the ends of the rods, as at m , and fit loosely in the slots the blocks 10 or boxes n , in which the wrist-pins o of the lever O are loosely fitted, and so that when the set-screws P , which pass through the edges of the rods against the blocks n , are loosened, the blocks may be shifted in the slots, as required, whereupon the blocks are again fastened by the screws P . (See Figs. 3 and 4.) 15 Nuts p on the pins o hold the rods $M M'$ to the lever.

The lever O in Figs. 1 and 2 is arranged to 20 be rocked backward and forward; but the diagram, Fig. 5, shows the lever adapted to work up and down on a fulcrum, O' , fixed to the car-frame, the arrangement of the friction driving-wheels and crank-shafts being the same as 25 above described. The diagram view, Fig. 6, also shows a horizontal arrangement of the working-lever O , but with the friction-wheels $J J'$ acting each upon its own driving-wheel K , one wheel K being provided on both the 30 forward and hind axles for propelling a four-wheeled car or vehicle.

The connections of the rods $M M'$ to the lever O and the cranks $e e'$ in Figs. 5 and 6 are to be substantially the same as above described 35 with reference to Figs. 1 to 4, inclusive, of the drawings.

Intermeshing toothed wheels or gearing may be substituted for the friction-wheels; but the latter are practically noiseless in action, and 40 hence are preferred.

It will be seen that with the relative proportions shown of the wheels $J J'$ and the wheel K the latter will be revolved about three times for every revolution of the former, 45 whereby a rapid revolution of the shaft D may be secured with a slow movement of the working-lever.

In driving machinery it will be connected by belts and pulleys or gear-wheels with the 50 shaft D , mounted with the lever, connecting-rods, cranked shafts, and friction-wheels in any suitable frame.

In applying the improvement to rocking chairs the opposite rods $M M'$ in Fig. 5 will 55 connect with the chair-seat at each side of the center of oscillation, so that a person seated in the chair may by rocking it drive the shaft D by the friction-wheels $J J' K$, and

power may be taken from the shaft by pulley and belt to drive a churn or sewing-machine, 60 or to do other light work.

Having thus described my invention, I claim as new and desire to secure by Letters Patent—

1. A hand-power mechanism constructed 65 with a drive-wheel mounted rigidly on a main shaft carrying a loosely-mounted rock-lever, and said lever being connected by rods with the reversely-set cranks of two shafts, each carrying wheels which act on the drive-wheel of 70 the main shaft, substantially as shown and described.

2. The combination, in a hand-power mechanism, of the shaft D , drive-wheel K , lever O , connecting-rods $M M'$, cranked shafts $E E'$, 75 and drive-wheels $J J'$, substantially as shown and described.

3. The combination, in a hand-power mechanism, of the shaft D , friction-wheel K , lever O , connecting-rods $M M'$, and cranked shafts 80 $E E'$, carrying the friction drive-wheels $J J'$, said shafts $E E'$ being mounted in boxes, allowing the wheels $J J'$ to yield, substantially as shown and described.

4. The combination, with the shaft D and 85 its drive-wheel K , of the oppositely-placed wheels $J J'$, mounted on cranked shafts $E E'$, which are journaled in boxes $F F'$, fitted to slide in bearings of the frame, substantially as shown and described.

5. The combination, with the shaft D , drive-wheel K , and opposite wheels $J J'$, mounted 90 on shafts fitted to sliding boxes $F F'$, as specified, of the springs H and means for compressing the springs on the boxes, substantially 95 as shown and described.

6. The combination, with the boxes $F F'$ and springs H , of the set-screws I , substantially as herein shown and described.

7. The combination, with the lever O , fitted 100 loosely on the shaft D , and the cranked shafts $E E'$, fitted in the sliding boxes $F F'$, as specified, of the connecting-rods $M M'$, slotted at m , and held to the lever at opposite sides of the shaft D by the adjustable blocks n , and means 105 for adjusting the blocks, substantially as shown and described.

8. The combination, with the lever O , having pins o , and the connecting-rods $M M'$, slotted at m , of the blocks n , set-screws P , and 110 nuts p , substantially as herein shown and described.

ELI Z. WHITE.
